UNITED STATES PATENT OFFICE

JACOB FINK, DECEASED, LATE OF ST. PAUL, MINNESOTA, BY ROSE J. FINK, ADMINISTRATRIX, OF ST. PAUL, MINNESOTA

METHOD OF CONSTRUCTING LEG COVERING GARMENTS

Application filed November 6, 1929. Serial No. 405,107.

This invention relates to a method of constructing a leg covering garment of the type described in Patent No. 1,705,008, dated March 12th, 1929, to Jacob Fink, now deceased, and particularly to a method of constructing the pattern for such a garment whereby a full and properly fitting seat and crotch of the garment is formed.

It is the object of this invention to facilitate the construction of a garment of the class described, with economy in the use of material, while insuring the formation of a garment which properly conforms to the figure and allows freedom of movement of the wearer without unsightly looseness of material.

The invention will be best understood by reference to the accompanying drawings in which the device is particularly illustrated as employed in the construction of a garment of the type known as a knickerbocker.

In the drawings, Figure 1 is a rear view of the improved garment; Fig. 2 is a fragmentary, top, plan view of the crotch of the garment; Fig. 3 is a plan view of a typical pattern for the entire garment; Figs. 4, 5 and 6 illustrate successive steps in the formation of the pattern for the rear of the garment, including the seat piece and rear part of the leg covering members and Fig. 7 is a plan view of the several members of the garment laid out in their relative positions for sewing together.

The garment, as best shown in Fig. 7, is formed from a seat piece 8, rear elements 9 and front elements 10 of leg covering members. Edges 11 of the seat piece 8 are sewed to edges 12 of the elements 9 and edges 13 of the members 10 are sewed to edges 14 of the elements 9 and the upper portions of said edges 13 may be secured to side edges 15 of the seat piece 8. Edges 16 of the members 10 are joined together at the front of the garment to form a front seam extending from the front of the waist line to the crotch of the garment. Inside leg seams are formed by joining the edges 17 of the members 10 to edges 18 of the elements 9. As shown in Figs. 1 and 2, a pointed lower end 19 of the seat piece 8 overlaps angular projections 20 of the mem-

bers 10 to form a reinforced crotch in which the extremities of the projections 20 meet at a central point and a minimum of overlapping seams is provided.

Proper fitting of the garment is dependent largely on the construction of the seat piece 8 and adjoining edges of the elements 9. To insure proper fitting of the garment, I lay out a pattern as illustrated in Figs. 3 to 6 inclusive. The first step (shown in Fig. 4) in the process is to lay out a pattern 21 for the rear of one of the leg covering members and including the material for the seat piece pattern. The pattern thus laid out or drawn includes an edge 22, representing the center line of the back of the garment; an edge 23, representing a portion of the waistline; an edge 24, representing the line corresponding to an outside leg seam, an edge 25 at the leg opening and an inside seam edge 26 extending to a point or corner 27 at the junction of the center line 22. From the point 27 is then drawn a line 28 representing the side edge of the seat piece and extending above the waistline edge 23 in a projection defined by the lines 29.

As shown in Fig. 5, the next step is to cut the seat piece along the lines 22, 28 and 29 so that the severed piece 30 may be moved to a position like that taken by the seat piece in the finished garment. Thus the seat piece pattern may be moved down to overlap the corner 27 and upper extremity of the edge 26. Where an undergarment or other loose fitting garment is desired, the piece 30 and remainder of the member 21 may be employed as the completed pattern for the seat piece and rear of the leg covering member. Thus an edge 31 on the seat piece 30 and an edge 32 on the leg member 21 are formed in the pattern and the corresponding edges of the fabric, when sewed together, produce the desired fullness and reinforced crotch such as that illustrated in Fig. 2. In order to secure edges 31 and 32 together in the crotch it is necessary to move the corner 27 and the lower end or crotch portion of the seat piece rearwardly or forwardly out of the position in which the seat piece and leg covering members lie flat, as illustrated in Fig. 5. Otherwise stated, and with particular reference to Fig. 7, it is

necessary, in order to secure the lower portions of the edges 11 of the seat piece to the edges 12 of the crotch corners of the elements 9, to move the pointed end 19 and the 5 crotch corners of the elements 9 transversely out of the position where they would normally lie flat in overlapping relation to each other.

- When a closer fitting garment is desired,
- 10 the edge 31 of the seat piece 30 may be cut away, as indicated by the line 33 in Fig. 5 and an extension 34 of the line 33 may be made across the upper part of the member 21. The seat piece 35 of the pattern, as shown in 15 Fig. 6, may now be formed by tracing the lines 22, 23, 33 and 34 at the same time defining the modified leg covering member 36 with the original edge defined by line 32 merging into the edge corresponding to line 20 34. This completes the formation of the patterns for the seat piece 8 and element 9 of the leg covering member, it being understood that the garment is symmetrical about the center line 22. The member 10 is finally laid 25 out and may, if desired, be superimposed upon the pattern 21 for the rear of the garment, as indicated by the dotted lines 37, 38 and 39 in Fig. 3. Proper fitting together of the front and rear elements of the leg covering 30 members is facilitated by the construction illustrated in Fig. 3, the pattern of the member 10 being traced from the lines 37, 38, 39 and connecting outline of the pattern 21. Where a reinforced crotch is not desirable or 35 necessary the pointed end 19 of the seat piece 8 may be omitted or cut off so that its lower end conforms to the inside leg seams.

The invention is used advantageously in the construction of undergarments for men, 40 women or children, or for trousers, bloomers, knickerbockers or other external garments. It has obvious advantages in constructing garments for outing or sport wear.

Having described the invention of said 45 JACOB FINK, deceased, what is claimed as new and desired to be protected by Letters Patent is:

1. The method of constructing a leg covering garment, having leg covering and seat members, which comprises, laying out the 50 pattern for the rear part of one of the leg members, said pattern having edges representing the waistline and center line of the back of the garment, laying out on the surface of the pattern so formed and extending 55 along said center line a pattern for a seat piece, allowing material to project above the waistline for the upper part of the seat piece, forming a seat piece and a leg covering member from said patterns and moving said seat piece downward from its corresponding position in the pattern relative to said first mentioned pattern and joining the edges of the seat piece and leg member together in 60 their new relative positions.

2. The method of constructing a leg covering garment, having leg covering and seat members, which comprises, laying out the pattern for the rear part of one of the leg members, said pattern having edges representing the waistline and center line of the back of the garment, laying out on the surface of the pattern so formed and extending along said center line a pattern for a seat piece, the latter pattern having its lower end 70 formed by a line extending obliquely upward from said center line, allowing material to project above the waistline for the upper part of the seat piece, forming a seat piece and a leg covering member from said patterns and moving said seat piece downward from its corresponding position in the pattern relative to said first mentioned pattern and joining the edges of the seat piece and leg member together in their new relative 75 positions.

3. The method of constructing a leg covering garment, having leg covering and seat members, which comprises, laying out the pattern for at least a part of one of the leg members, said pattern having edges representing the waistline and center line of the back of the garment, laying out on the pattern so formed and cutting therefrom a pattern for a seat piece extending along said center line, forming an extension of the seat piece projecting above the waistline and utilizing the outline of the seat piece and leg members thus produced in the construction 90 of the garment.

4. The method of constructing a leg covering garment having leg members and a seat piece, which consists in laying out the pattern for at least the rear part of one of the leg covering members, one side edge of said pattern representing the center line of the back of the garment, and the pattern having a crotch corner at the lower end of said center line, laying out on the margin of said pattern adjoining said edge a pattern for a seat piece by drawing a line from said corner obliquely upward toward the waistline, constructing seat and leg covering members from said patterns and securing the corner of said leg covering member corresponding to said corner of the pattern to the side edge of the seat at a point removed from the lower end thereof.

5. The method of constructing a leg covering garment, having leg covering and seat members, which comprises, laying out the pattern for at least a part of one of the leg members, said pattern having edges representing the waistline and center line of the back of the garment, laying out on the pattern so formed and cutting therefrom a pattern for a seat piece extending along said center line and having a side edge extending obliquely upward from the lower end of said center line, forming an extension of the seat 125 130

piece projecting above the waistline and utilizing the outline of said patterns in the construction of the seat piece and leg members of the garment.

6. The method of constructing a leg covering garment having leg members and a seat piece which consists in forming similar leg covering members having corners projecting toward the center line of the garment in the crotch, placing a seat piece to conform at portions of its side edges to the rear edges of said members, said piece having a crotch portion overlapping said projections when laid flat and with said members and piece in position for assembling in the garment, securing said seat piece to the rear edges of said leg covering members and securing the side edges of said crotch portion to the side edges of said corners while moving overlapping portions transversely out of said flat position to give fulness to the crotch.

7. The method of constructing a leg covering garment having leg members and a seat piece which consists in forming a leg covering member having a corner projecting from the rear edge of the same toward the center line of the garment in the crotch, said corner having upper and lower converging edges extending obliquely toward said center line, placing a seat piece to be secured to the rear edge of said member with a crotch portion of said piece overlapping said projection when laid flat and with said member and piece in position for assembling in the garment, securing said seat piece to the rear edge of said leg covering member and securing the side edge of said crotch portion to the upper side edge of said corner while moving said overlapping portion transversely out of said flat position.

40 In testimony whereof, I have hereunto signed my name to this specification.

ROSE J. FINK,
Administratrix of the Estate of Said Jacob
45 Fink, Deceased.
